UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

FRICITION DRAFT-RIGGING FOR RAILWAY-CARS.

No. 909,816.

Specification of Letters Patent.

Patented Jan. 12, 1909.

Application filed March 23, 1908. Serial No. 422,600.

To all whom it may concern:

Be it known that I, JOHN F. O'CONNOR, a citizen of the United States, residing in Chicago, in the county of Cook and State of Illinois, have invented a new and useful Improvement in Friction Draft-Rigging for Railway-Cars, of which the following is a specification.

My invention relates to improvements in friction draft rigging.

In friction draft rigging heretofore in use, after the friction devices become somewhat worn and thus reduced in size, a considerable amount of slack or lost motion accumulates which materially interferes with and reduces the effectiveness of the draft rigging in practical operation, and also prevents the draw bar from being fully restored to its normal position when the spring expands, because of the looseness of the parts and reduction in size of the friction devices which are interposed between the spring and the draw bar.

The object of my invention is to provide a friction draft rigging by which these difficulties or objections may be practically overcome, and wherein the slack, lost motion and reduced size of the friction devices due to wear will be automatically taken up and compensated for, so that the parts, including followers, spring and friction devices, will always remain in close contact with each other and in position for effective operation.

A further object is to provide a friction draft rigging wherein the main spring of the draft rigging will always hold the friction devices under an initial load and thus prevent movement of one friction device in respect to the other without also producing an initial frictional resistance, so that the friction devices may thus operate with increased efficiency throughout the total movement of the draw bar from beginning to end.

A further object is to provide a friction draft rigging of a simple, efficient and durable construction, by which the above results may be accomplished, and which will also have provision for properly cushioning light strains or blows without operating the frictional resistance mechanism, as well as provision for properly cushioning heavy or violent blows or strains through the action of the main spring and the frictional resistance.

My invention consists in the means I em-

ploy to practically accomplish this object or result, as herein shown or described, the same consisting essentially in the combination with the draw bar, draw bar yoke, followers and stops or draft lugs for the followers to abut against, of a main draft rigging spring, friction devices against which said spring acts, and preferably comprising a friction shell, friction blocks or shoes within the shell, and a wedge or spreader block acting against the shoes, and a connecting rod operating upon the wedge or spreader block to hold the main spring under an initial compression and the friction shell and friction shoes or blocks under an initial pressure or frictional engagement, so that the friction members cannot move in respect to each other without producing effective frictional resistance; and so that as the friction devices become smaller by wear the slack or lost motion will be automatically taken up and compensated for by expansion of the main spring as to a part of its initial tension or compression.

It further consists in connection with these parts, of a preliminary compression spring preferably interposed between the wedge and the front follower to enable the draft rigging to effectively cushion light blows without necessarily moving the friction devices or compressing the main spring.

It further consists, in connection with these parts, of a preliminary compression follower or thimble for the preliminary compression spring, having a shoulder or end to engage the wedge or spreader block and limit the compression of the preliminary compression spring.

It further consists in providing this preliminary compression follower or thimble with a non-circular projection or extension which enters a similarly shaped socket in the wedge to prevent the wedge and adjacent parts from turning or revolving, and thus insuring the antifriction rollers being kept in horizontal position or in proper relation to the other parts.

The invention further consists in the novel construction of parts and devices and in the novel combinations of parts and devices herein shown and described.

In the accompanying drawing, forming a part of this specification, Figure 1 is a side elevation, partly in central vertical

longitudinal section of a friction draft rigging embodying my invention; Fig. 2 is a plan view with the draw bar yoke partly broken away to better show the parts; Fig. 5 10 is a cross section on line 3—3 of Fig. 1; Fig. 4 is a detail perspective view of the preliminary compression follower; Fig. 5 is a detail perspective view showing a modification in which the preliminary compression follower and front follower are made integral.

In the drawing A represents the center sills of a car, A¹ the front or end sill, B the draw bar, B¹ the draw bar yoke, C C, 15 C¹ C¹ and C² C² C³ C³ the front, rear and intermediate stops or draft lugs secured to the center sills for the followers D D¹ to abut against.

E E¹ are the main draft rigging springs. 20 F is a longitudinally movable friction shell, F¹ F¹ friction blocks within the shell, F² a wedge or spreader block, E² a supplemental preliminary compression spring interposed between the wedge F² and the front 25 follower D and surrounding a thimble or preliminary compression follower D².

G is a connecting rod between the thimble D² and the rear end of the friction shell F for holding the main draft rigging 30 spring E E¹ under an initial tension and all the parts assembled.

H H are antifriction rollers interposed between the inclined or wedging faces f of the friction blocks F¹ and the inclined faces 35 f¹ of the wedge or spreader block F².

The friction shell F preferably has an external recess or countersink f² in its rear head or end f³ to accommodate the threaded nut g of the connecting bolt G and forming 40 an internal boss f⁴ which fits inside the outer or main spring E, thus forming an annular seat for the rear end of said spring. The smaller main spring E¹ which fits inside the outer spring E, abuts against the inner end of 45 this inwardly projecting boss f⁴, and at its front end the inner spring E fits in a circular recess f⁵, with which the friction blocks F¹ F¹ are provided at their inner or rear ends. The spring E thus extends beyond 50 the spring E¹ at the rear end, while the spring E¹ extends beyond the spring E at the front end, as will be readily understood from Fig. 1.

The wedge or spreader block F² is provided at its front end with a noncircular, 55 preferably rectangular, cavity or recess f⁶ to receive the corresponding projection d on the inner end of the thimble D², so that the thimble may telescope with the wedge F² sufficiently to permit compression and 60 expansion of the preliminary compression spring E². The noncircular or rectangular form of the projection d and recess f⁶ prevents the wedge from turning in respect to 65 the thimble D². And, as the friction block

F¹ cannot turn in respect to the wedge F², this construction also serves to keep the friction blocks in proper position.

The preliminary compression follower or thimble D² is preferably made in a separate 70 piece from the front follower D, and furnished with an integral flange or plate member d¹, having horizontal upper and lower edges d² fitting within and engaging the inner faces of the yoke B¹, so that the thimble cannot turn in respect to the yoke. 75

The preliminary compression follower D² abuts at its inner end d⁴ against the wedge or spreader block F², and thus serves to limit the compression of the preliminary 80 spring E², and to transmit the main pressure of the draw bar to the wedge. The flange or plate portion d¹ of the preliminary compression follower D² also serves by its engagement with the end of the friction shell 85 F to limit the compression of the main draft rigging springs E E¹, so that said springs E E¹ cannot be compressed solid and thus cause the wedge F² through the friction blocks F¹ to exert a destructive or 90 bursting strain upon the friction shell F. The intermediate stops C² C³ by engagement with the followers D D¹ by limiting the movement of the draw bar also relieve the friction shell from compression blows 95 tending to shorten the friction shell in length and thus interfering with its proper co-operative action with the other parts.

In practice the main draft rigging springs E E¹ preferably have about two and one-half 100 inch total movement or compression, and in the assembled gear these springs are held under an initial compression of about one-half inch by the connecting rod G. In practice I prefer to have the connecting rod G act 105 upon the wedge F² through the preliminary compression follower D² and interposed compression spring E², instead of having this connecting rod act directly against the wedge, as by this arrangement the connecting rod G will also serve the function of holding the preliminary compression spring 110 E² and the preliminary compression follower D² all in assembled position with the other parts. The connecting rod thus also 115 serves to hold or keep the cushioning devices, as a whole, of a predetermined and fixed length over all, that is to say, from the rear end of the friction shell F to the front end of the preliminary compression follower 120 or thimble D².

The thimble D² is provided with a central recess d³ to receive the head or front end g¹ of the connecting bolt G. The connecting bolt G is provided with a washer or plate G¹ 125 at its rear end which fits in the recess f² in the rear head or end f³ of the friction shell F.

K K are tie plates removably secured to 130 the center sails by bolts K¹, and which sup-

port the draft rigging through the followers.

The flange or plate d^1 on the thimble D^2 has elongated side wings d^5 to prevent its being assembled wrong side up, in respect to 5 the other parts.

In the modification illustrated in Fig. 5, the thimble D^2 is shown as being made integral with the front follower D.

I claim:

10 1. In a friction draft rigging, the combination with a spring, of a friction shell, friction shoes within the shell, a wedge and a connecting rod operating through the wedge to hold the spring normally under 15 an initial compression to automatically take up wear of the friction devices and maintain the draft rigging of standard length, substantially as specified.

20 2. In a friction draft rigging, the combination with a spring, of a friction shell, friction shoes within the shell, a wedge and a connecting rod operating through the wedge to hold the spring normally under an initial compression, a preliminary compression spring, and a preliminary compression follower, said connecting rod acting upon the wedge through said preliminary compression follower and preliminary compression spring to automatically take up wear 25 of the friction devices and maintain the draft rigging of standard length, substantially as specified.

30 3. In a friction draft rigging, the combination with the draw bar, yoke and followers and front and rear intermediate stops for the followers to abut against, of a longitudinally movable friction shell, a spring, friction blocks, a wedge, antifriction rollers between the wedge and friction blocks, a 35 connecting rod acting through the wedge to hold the spring normally under an initial compression to automatically take up wear of the friction devices and maintain the draft rigging of standard length, a preliminary compression spring and a preliminary compression follower to which the connecting rod is attached, substantially as specified.

40 4. In a friction draft rigging, the combination with a draw bar, draw bar yoke

and followers, of a spring, a friction shell, 50 friction shoes and wedge within the shell, a connecting rod between said shell and wedge and operating to hold the spring under an initial compression, a preliminary spring a thimble within said preliminary spring operating as a stop to limit its compression, and to which said connecting rod is attached, 55 said connecting rod operating through said wedge and thimble to hold said springs normally under an initial compression and to automatically take up wear of the friction devices and to maintain the draft rigging of standard length substantially as specified.

5. In a friction draft rigging, the combination with the draw bar, draw bar yoke 60 and followers, and front, rear and intermediate stops for the followers to abut against, of a longitudinally movable friction shell, a spring, friction blocks and wedge and antifriction rollers within the shell said wedge 65 having a non-circular recess, and a supplemental preliminary spring interposed between the wedge and the adjacent follower, a thimble within said supplemental spring having a noncircular projection fitting with 70 in a noncircular recess in said wedge, and a connecting bolt extending between said thimble at one end and the opposite end of said friction shell, whereby all the parts are held assembled, substantially as specified. 75

6. In a friction draft rigging, the combination with a spring, friction shell inclosing said spring and against which the spring bears at one end, friction blocks within said shell bearing against the opposite ends of 80 the spring, a wedge, antifriction rollers, a follower, a preliminary compression spring between said wedge and said follower, and a thimble for said preliminary compression spring furnished with a non-circular projection, said wedge having a noncircular recess 85 to receive said projection, substantially as specified.
